[57] CLAIM

The ornamental design for a notebook computer, as shown and described.

DESCRIPTION

FIG. 1 is a perspective view from the front-left-top side of a notebook computer showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a perspective view of the notebook computer, where a keyboard is pivotally lifted up for illustrative purpose only.
